2 SHEETS—SHEET 1.

TO FIND THE NUMBER OF DAYS BETWEEN ANY TWO GIVEN DATES IN THE SAME YEAR: Take the difference between the accompanying index numbers.

If the given dates are in different but consecutive years, take the difference between the accompanying index numbers and subtract this result from 365. In leap year, if the period involves February 29th, add one day to the result in each case.

TO FIND THE DATE OF MATURITY IN THE SAME YEAR: Add to the index number of the given date the number of days to run. The result will be the index of the required date.

If the required date is in the following year: Add to the index number of the given date the number of days to run and subtract 365 from this result. In leap year, if the period involves February 29th, subtract one in each case.

TO FIND THE NUMBER OF DAYS TO NEXT INTEREST PERIOD:

Find the given date in the time schedule at the left. The corresponding number in the nearest "days column" is the required number. In leap year, should the period involve February 29th, add one day.

This feature is applicable especially to the use of the card with the Coupon Certificate of Deposit.

The numbers at the top of the squares are index numbers.

ILLUSTRATION

Required—The interest on \$7,984 for 17 days.

In the days column, near the left, find 17. Follow the line of this no. continuously to the right.

Under 7000 you will find $-\$19.83$

" 900 " " " - 2.55

" 80 " " " - .25

" 4 " " " - .01

find that the interest on 7984 for 17 days is $\$22.62$ By simple addition you

UNITED STATES PATENT OFFICE.

WALTER SPARKLIN, OF PETERSBURG, VIRGINIA.

INTEREST AND TIME CALCULATING SHEET.

No. 927,693.

Specification of Letters Patent.

Patented July 13, 1909.

Application filed August 5, 1908. Serial No. 447,178. (Specimens.)

To all whom it may concern:

Be it known that I, WALTER SPARKLIN, a citizen of the United States, residing at Petersburg, in the county of Dinwiddie and State of Virginia, have invented new and useful Improvements in Interest and Time Calculating Sheets, of which the following is a specification.

This invention pertains to interest calculating sheets and has for its purpose the provision of such a table whereby interest may be readily computed upon a given amount for a given period.

The further object of the invention is to so arrange the indicia that a complete calculation may be made while the sheet is held conveniently in view; and to accomplish this result without the use of mechanical means, such as slide rules, pointers, etc., that are usually employed on devices for this purpose.

Other advantages attending the use of my interest calculator are that it offers the shortest, simplest, most accurate and practical method of computing interest. It is especially adapted for use in connection with the adjustable coupon certificate of deposit, a modern banking device for time deposits, the use of which increases deposits by offering large inducements to depositors, makes more business with less labor and cost, simplifies the bookkeeping and reduces it to the minimum, thereby practically eliminating errors and dishonesty among employees, and makes banking-by-mail easy.

With these and subordinate advantages hereinafter explained my invention embodies the arrangement and disposition of data shown on the accompanying sheet, the details of which are pointed out in the following specification and set forth in the claims.

In the fac-simile submitted, Figures 1 and 2, designate the sheet in its entirety, disclosing the system.

Since the data shown on Fig. 2 is merely the calendar continuation and computations therefor of that shown on Fig. 1, it will be necessary to describe in detail only Fig. 1. In this view A refers to the table having four decimal sections or columns headed "Thousands", "Hundreds", "Tens", and "Units", running from left to right and indicated by B, C, D, and E, respectively. In the left hand or "thousands" section are ten (10) vertical sub-columns F, intersected by horizontal columns F' providing blocks, in which

are inserted in black figures as at a, various numbers, indicating the amount of interest for various numbers of days, and at the heads of these columns and above each of the black numbers referred to, are the primary digits in red b, denoting the number of thousands; i. e. in the first or left hand column, over each number in black, is the number "10" in red, indicating that the numbers in black show the interest on \$10,000 for the various numbers of days consecutively. In the second sub-column of the section B, over each number in black, is the figure "9" in red, indicating that the numbers in black give the interest on \$9,000 for the respective number of days. In like manner, each sub-column in this section, represents the interest on the number of thousands, shown by the red figures in that column. The second, or hundreds section C, has nine (9) sub-columns, similarly arranged, and indicating the interest on hundreds from nine to one respectively. The third or tens section D, bears a like relation to the interest on tens of dollars, and similarly, the last or units section, shows the interest on dollars. Between these several sections B, C, D, and E, and to the left of the thousands section B, are columns G having figures c in black but of larger size than those heretofore mentioned, which figures indicate the number of days,—on the face of the card A (Fig. 1) from 1 to 60, and on the back of the card (Fig. 2) from 61 to 123, thus making calculation available by this method, for a period of any four months. The method of ascertaining the interest by the use of this card is shown in the following illustration:

Required—the interest on \$7,984 for 51 days, 6%.

In the days column, near the left, find 51. Follow the line of this number continuously to the right.

Under 7000 you will find	\$59.50	100
" 900 "	" " " 7.65	
" 80 "	" " " .68	
" 4 "	" " " .03	

By simple addition you find that the interest on \$7984 for 51 days is \$67.86.

A separate card is provided for each rate of interest and by the use of the proper card, according to the required rate, the interest of any amount up to \$10,000, and for any time up to 123 days, can be formed almost instantly. This interest computing card is

primarily intended for use in connection with the adjustable coupon certificate of deposit system wherein for instance there are three interest dates in the year, namely May 5 1st, September 1st, and Jan. 1st, but it may just as readily be adapted to a four per cent. rate of interest with the interest dates on Jan. 1st, April 1st, July 1st, and Oct. 1st. For the purpose of determining the number 10 of days for which the interest is desired, there is arranged on the left hand margin of the table A a time schedule II consisting of three columns *d*, *e* and *f*, entitled "Time to next interest date"; the three columns 15 themselves being sub-titled "May 1st, September 1st, and Jan. 1st", and under these sub-titles are given in black as at *g* their preceding dates in inverse order. Thus the left hand column *d*, headed May 1st, reads 20 "Apr. 30th, 29th, 28th," etc. Suppose it shall be desired, on April 3rd, to ascertain the number of days to the next interest date: Find Apr. 3rd in this schedule and take the corresponding number in the days column 25 *G*, immediately at the right of this schedule, which, in this instance, is 28, showing that on Apr. 3rd interest to the next date must be reckoned for twenty-eight days.

To further extend the usefulness of this 30 system to ordinary banking and general accounting, the days of the year are given in this schedule in red figures at *h*, in connection with the days of the respective months; thus the 12th day of April is shown at *x* by the red number immediately above to be the 35 102nd day of the year; therefore, to determine the number of days between any two dates, it is necessary only to take the difference between the accompanying numbers in red, which are termed the index numbers. And to determine the maturity of a note, with given date, at so many days, it is necessary only to add to the index number of the 40 date of the note, the number of days the note has to run, and the result will be the index of the required date. Of course, in 45 leap year, account must be taken of the 29th of February; and also when the periods run over from one year to the next, allowance 50 should be made for the difference of the days in the year. Thus if the required date is in the following year, add to the index number the number of days to run and subtract 365 from this result. In leap year, if 55 the period involves Feb. 29th, subtract one.

Having thus set forth the purpose of my invention and detailed its method of use, what is claimed as new is:

1. In a system for computing interest, a 60 table divided into sections containing interest amounts and indicia therefor, day columns adjacent said sections, and a time schedule column sub-divided into a plurality of monthly columns, the dates of the month

therein alining with the numbers in the day 65 columns whereby intervening time between interest periods may be determined.

2. In a system for computing interest, a table containing interest amounts and indicia therefor, a day column having indicia 70 alined with the corresponding interest amounts in the table, and a time schedule divided into a plurality of monthly columns having the dates thereof arranged in inverse order, said dates having associated therewith indicia designating the year dates of the several days whereby interest calculations may be made upon said table. 75

3. In a system for computing interest, a table divided into decimal sections, said sections subdivided into columns containing the primary digits, said digits having associated therewith amounts representing interest, a day column having indicia alined with the corresponding interest amounts in 80 the table, and indicia for determining the dates of maturity thereof.

4. In a system for computing interest, a table divided into decimal sections, said sections sub-divided into columns containing 90 amounts representing interest, the primary digits heading said interest columns, and a time schedule column, a day column having indicial alined with the corresponding interest amounts, adjacent said sections whereby interest calculations may be determined. 95

5. In a system for computing interest, a table divided into decimal sections, said sections sub-divided into columns containing 100 the primary digits, said digits having associated therewith amounts representing interest, a time schedule column adjacent said sections, said column divided into monthly periods, and day columns intermediate said sections and adjacent the schedule column 105 whereby the number of days to the next interest period may be determined.

6. In a system for computing interest, a table divided into decimal sections, said sections sub-divided into columns containing 110 the primary digits, said digits having associated therewith amounts representing interest, and a time schedule column adjacent said sections, said schedule column being sub-divided into a plurality of monthly columns having the dates of said months arranged in inverse order, said dates having associated therewith numbers designating the year dates thereof, whereby the number 115 of days between given dates may be computed for calculating interest. 120

In testimony whereof I have hereunto set my hand in presence of two subscribing witnesses.

WALTER SPARKLIN.
